UNITED STATES PATENT OFFICE.

JOSHUA HEATH, OF SYDNEY, AND FRANCIS JOHN BOYLE, OF NORTH SYDNEY, NEW SOUTH WALES, AUSTRALIA.

INFANT SLING-SUPPORT.

1,109,065.

Specification of Letters Patent.

Patented Sept. 1, 1914.

Application filed August 12, 1913. Serial No. 784,378.

To all whom it may concern:

Be it known that we, JOSHUA HEATH, a subject of the King of Great Britain and Ireland, residing at 549 George street, Sydney, in the State of New South Wales, Commonwealth of Australia, and FRANCIS JOHN BOYLE, a subject of the King of Great Britain and Ireland, residing at 269 Alfred street, North Sydney, in the State of New South Wales, Commonwealth of Australia, have invented certain new and useful Improvements in Infant Sling-Supports, of which the following is a specification.

The practice of carrying an infant upon the arm is found to be a tiresome duty, particularly so in hot climates, and is to many women undoubtedly an injurious one, and occasionally liable to be hurtful to the child.

According to this invention the infant sling support consists of a shoulder strap of flexible material, adjustable longitudinally, the ends of which support at a distance approximately level with the waist of the wearer a seat preferably of leather or like strong and flexible material.

For the purpose of securing the child upon the seat a band is attached to the sling member which band is positioned to take around the body of the infant, and is adjustable vertically.

Referring to the sheet of drawings depicting an infant sling support according to the present invention: Figure 1 is a perspective view. Fig. 2 a longitudinal sectional elevation, and Fig. 3 a transverse sectional elevation.

The sling member 5 of webbing, leather, or other like strong flexible material is adjustable longitudinally by means of the buckle 6. The ends 7 of this sling member 6 are each terminally provided with a ring

8 to which are attached the double straps 9 the lower ends of which are attached to the seat 10 of leather or other light strong flexible material. The band 11, adjustable circumferentially by the buckle 12, embraces the body of the child under the arms and retains the child in position upon the seat 10 being passed through a pair of loops or keepers 13 attached to the cross bar of the 50 buckles 14 which buckles secure same to the sling member 5 and permit of vertical adjustment of said band 11.

In use, the sling member 5 being in position upon one shoulder and the seat 10 positioned on the opposite side of the wearer's body and the infant secured in position upon said seat by the band 11 it will be found that the child may be carried with greater ease than hitherto. Furthermore, 60 the construction of the sling support and materials composing same are such that the support can be manufactured and sold at a price within the scope of all pockets.

What we claim and desire to secure by 65 Letters Patent is:—

An improved infant sling support comprising in combination an adjustable shoulder strap, a seat for the infant dependent from the ends of said strap, and an adjustable band to encircle the infant and loops attached to adjustable buckles on the said shoulder strap through which said band is passed, as herein set forth.

Signed at Sydney, New South Wales, this 75 11th day of July 1913.

JOSHUA HEATH.
FRANCIS JOHN BOYLE.
